COMBINED WATER HEATER AND HEAT DEFLECTOR ATTACHMENT FOR FURNACES

Raymond F. Sturgis, Elizabeth, N. J., assignor to Michael A. Lisena, Newark, N. J.

Application May 8, 1935, Serial No. 20,459

5 Claims. (Cl. 122—165)

This invention relates to certain new and useful improvements in a combined water heater and heat deflector attachment for furnaces.

The primary object of the invention is to provide a combined water heater and heat deflector attachment for furnaces of the type originally designed for the burning of coal, but converted for the burning of oil and in many instances when a coal burning furnace is converted into use as an oil burner, no provision is made for the complete utilization of heat units which flow by draft when oil is used as compared with slowly burning coal, the present invention providing an auxiliary water chamber directly in the path of the oil burner flame and a deflector for directing the flame and heat units onto the water jacket of the furnace.

A further object of the invention is to provide a heating apparatus of the foregoing character for use with either hot water or steam furnaces, the latter being illustrated by way of example in this application with a piping system for drawing water from the head of the furnace downwardly to the auxiliary heater for superheating thereof and for creating a partial vacuum or suction in the steam pipes and radiators for withdrawing condensation and air from the radiators into the auxiliary water heater.

A still further object of the invention is to provide a heating apparatus of the foregoing character with the combined water heater and heat deflector designed for directing the flame and heat units from the oil burner onto the auxiliary water heater and water jacket of the furnace with fire brick deflectors superposed on the auxiliary water heater for increasing the area of the direct contact of the heat units with the water jacket of the furnace to reduce the consumption of fuel and substantially utilize all heat units before escape from the furnace to the chimney.

With the above and other objects in view that will become apparent as the nature of the invention is better understood, the same consists in the novel form, combination and arrangement of parts hereinafter more fully described, shown in the accompanying drawings and claimed.

In the drawings:—

Figure 1 is a vertical sectional view of a steam heating furnace originally designed for the burning of coal and converted into an oil burner with the combined water heater and heat deflector attachment therein, the water heater being supported within the furnace by pipes forming a part of the circulating system;

Figure 2 is a horizontal sectional view taken on line 2—2 of Figure 1 showing fire brick deflectors mounted on the auxiliary heater and spaced from the water jacket of the furnace;

Figure 3 is a perspective view of the auxiliary water heater showing the ribbed pockets on the periphery thereof for the support of spacer bricks to centrally position the water heater within the furnace in spaced relation to the water jacket;

Figure 4 is a bottom plan view of the conical heat deflector supported centrally of the auxiliary water heater; and

Figure 5 is a fragmentary vertical sectional view, similar to Figure 1, showing the auxiliary water heater supported by pipes rising therefrom and engaged with the water legs of the furnace to form direct communication between the auxiliary water heater and water legs.

While the combined water heater and heat deflector attachment may be associated with hot water furnaces, the same is herein illustrated as mounted in the furnace of a steam heating system, the furnace being of the coal burning type and embodying a base 10 enclosing the usual ash pit 11 with a cylindrical water jacket 12 supported on the base 10 and the steam dome 13 at the upper end of the water jacket, there being a central pipe outlet 14 for exhaust or products of combustion that leads to a chimney. Internal water legs 15 are carried by the water jacket 12. The piping system for the steam radiators or other heaters includes pipes 16 for conveying steam from the steam dome 13 to the header pipes 17 from which branch pipes 18 extend to the radiators or other heaters.

The usual grate structure is removed from the furnace and a burner nozzle 19 from a forced draft oil burner extends into the ash pit area 11 of the furnace and is confined within the wall 20 for directing the flame upwardly into the furnace. The auxiliary water heater 21 shown in detail in Figure 3 is in the form of an annular water channel having a stepped central opening therein defining a relatively narrow annular rib 22 at the upper end thereof surrounding the central opening 23. A conical deflector 24 is seated in the upper end of the opening 23 in the water heater and is provided with ribs 25 upon its lower face to space the deflector from the wall of the opening 23 and to provide a restricted passage as 50 an aid to combustion. The water heater 21 is of less diameter than the water jacket 12 and is centrally positioned within the water jacket adjacent the lower end and spaced therefrom by means of fire bricks 26 or the like that are seated 55

in U-shaped ribbed pockets 27 carried by the peripheral wall of the water heater as clearly shown in Figures 1 and 3.

To support the water heater in the furnace, there is provided a pair of pipes 28 and 29 extending upwardly from the furnace floor, the pipes being diametrically located with the upper end of the pipe 28 terminating at the bottom wall of the water heater, while the upper end of the pipe 29 extends into the water heater as at 38 and terminates adjacent the upper end thereof. The water level in the water jacket 12 is at the base of the steam dome 13 and a pipe 31 forms communication between the upper end of the water jacket slightly below the water level and the supporting pipe 29 for purposes presently to appear. A vertical pipe 32 has its upper end in communication with the steam header 17 while the lower end thereof enters a T-fitting 33, the other end of the T-fitting having a nipple connection 34 with the lower end of the water jacket 12 while the side of the T-fitting has a pipe connection 35 with the supporting pipe 28 and in which pipe connection 35, a check valve 36 is interposed. The water in the water jacket also seeks its level in the pipe 32 as shown in Figure 1.

The water heater 21 and deflector 24 act to direct the major portion of the flame and heat units from the burner onto the water heater and outwardly thereof into contact with the inner face of the water jacket 12 and to increase this area of contact, fire bricks are supported on the upper side of the water heater 21 as shown in Figures 1 and 2. The superposed fire brick is formed of two semi-circular sections 37 that mate to form a ring and each section carries outwardly directed block projections 38 that engage the inner face of the water jacket 12 as shown in Figure 2, with the block projections 38 disposed above the spacer block 26. The flame and heat units passing upwardly between the water heater 21 and water jacket 12 are therefore directed over a larger area of contact with the water jacket by the fire brick sections 37.

The deflector 24 is slightly spaced from the walls of the opening 23 in the water heater to provide an air passage for products of combustion, but the major portions of the flame and heat unit are directed onto the water heater 21 and deflected thereby onto the water jacket 12. Maximum heat is absorbed by the water heater in the area of the annular rib 22 and the superheated water in such area flows downwardly through the pipe section 30 and upwardly through the pipe 31 to enter the water jacket 12 at the upper end thereof. This direction of flow of water outwardly of the water heater 21 by way of the pipe 31 promotes suction in the upper end of the pipe 28 which acts to draw water from the lower end of the water jacket and by way of the nipple 34 into the pipe 35 and upper end of pipe 28 into the water heater 21. It will therefore be seen that hot water at the upper end of the water jacket is drawn downwardly to circulate through the pipe 35 and into the water heater 21 for superheating and return flow by way of the pipe 31 to the upper end of the water jacket. With this arrangement, maximum heat is radiated to the water heater 21 and water jacket 12, aided by the fire bricks 37, resulting in a minimum consumption of fuel and accomplishing maximum results. The check valve 36 in the pipe 35 prevents any back flow of water from the heater 21 and assures the circuitous flow thereof in the direction stated.

In the form of invention illustrated in Figure 5, the stand pipes 28 and 29 for the support of the water heater 21 are eliminated and in lieu thereof, the water heater 21 is supported by hanger pipes 39 that depend from the water legs 15 for the support of the water heater 21 and to cause a direct flow of superheated water from the water heater 21 directly upwardly to the water legs 15. Also, in this form of the invention the pipe 31 is eliminated, but the water flows downwardly from the upper end of the water jacket 12 through the pipe 35 and by way of the check valve 36 to the pipe section 28a that communicates with the lower end of the water heater 21.

While there are herein shown and described the preferred embodiments of the present invention, it is nevertheless to be understood that minor changes may be made therein without departing from the spirit and scope of the invention as claimed.

I claim:

1. In a combined water heater and heat deflector attachment for furnaces, a furnace having an inclosing water jacket, a water heater in the furnace adjacent the lower end of the water jacket and having a central opening therein, a deflector set into the opening, U-shaped supports carried peripherally of the water heater and spacer blocks set in the supports and engaged with the water jacket to space the water heater therefrom, means supported on the water heater and spaced from the water jacket for increasing the wall area of direct contact of the products of combustion with the water jacket, and a burner in the furnace beneath the water heater.

2. In a combined water heater and heat deflector attachment for furnaces, a furnace having an inclosing water jacket, a water heater in the furnace adjacent the lower end of the water jacket and having a central opening therein, a deflector set into the opening, U-shaped supports carried peripherally of the water heater and spacer blocks set in the supports and engaged with the water jacket to space the water heater therefrom, means supported on the water heater and spaced from the water jacket for increasing the wall area of direct contact of the products of combustion with the water jacket, a burner in the furnace beneath the water heater, a pipe system extending from the furnace to heater elements and including a return pipe, means forming communication between the lower end of the water heater and the lower ends of the water jacket and return pipe and means forming communication between the upper end of the water heater and upper end of the water jacket.

3. In a combined water heater and heat deflector attachment for furnaces, a furnace having an annular water jacket, an annular water heater concentrically positioned in the furnace adjacent the lower end of the water jacket, means for spacing the water heater from the water jacket, a conical deflector supported centrally of the water heater, an annular fire brick structure supported on the water heater vertically aligned with the peripheral edge of the water heater for increasing the area of contact of the heat units with the water jacket and a burner in the furnace beneath the water heater.

4. In a combined water heater and heat deflector attachment for furnaces as set forth in

claim 3, characterized by blocks projecting outwardly of the annular fire brick structure for engagement with the inner wall of the water jacket for retaining the fire brick structure centered in the furnace.

5. In a combined water heater and heat deflector attachment for furnaces, a furnace having an enclosing water jacket, a water heater in the furnace adjacent the lower end of the water jacket and having a central opening therein, a deflector set into the opening, U-shaped sup-

ports carried peripherally of the water heater and spacer blocks set in the supports and engaged with the water jacket to space the water heater therefrom, a fire brick structure supported on the water heater and carrying outwardly projecting blocks engaged with the water jacket and some of said blocks resting on the blocks mounted in the U-shaped supports, and a burner in the furnace beneath the water heater.
